UNITED STATES PATENT OFFICE.

JOHN P. FARLEY, OF KANSAS CITY, MISSOURI.

COMPRESSION-FAUCET.

1,106,933.

Specification of Letters Patent. Patented Aug. 11, 1914.

Application filed October 25, 1912. Serial No. 727,892.

To all whom it may concern:

Be it known that I, JOHN P. FARLEY, a citizen of the United States, residing at Kansas City, in the county of Jackson and State of Missouri, have invented certain new and useful Improvements in Compression-Faucets, of which the following is a specification.

This invention relates to compression faucets and has for its object to produce a faucet in which provision is made to guard against the sudden forcible ejection of the water from the spout, in which wear on the valve is reduced to the minimum, in which provision is made to guard against leakage of water around the stem of the handle, and in which the handle is so connected to the stem that it can be pointed, when the valve is closed in the same direction as the spout.

With these objects in view and others as hereinafter appear, the invention consists in certain novel and peculiar features of construction and organization as herein-after described and claimed; and in order that it may be fully understood reference is to be had to the accompanying drawing, in which—

Figure 1, is a central vertical section of a compression faucet embodying my invention. Fig. 2, is a horizontal section through the handle portion of the device.

In the said drawing, 1 indicates the base of the faucet, the same having the customary chamber 2, and a stem 3 communicating with said chamber and depending from the base to be fitted in a lavatory bowl or other fixture. The faucet is provided with a hollow body 4 above the chamber 2, and a discharge spout 5, and arranged between the chamber 2 and hollow body is a partition or diaphragm 6 having a central passage 7 and an upwardly projecting wall or valve seat 8 marginally of said passage. Extending upwardly from the body vertically above the base is a hollow extension 9 which is internally threaded at 10, and the bore of the extension is enlarged at its upper end to form a recess 11, and seated horizontally on the bottom of said recess, is a metallic washer 12, and a compressible packing ring 13, the latter resting upon the washer and having a depending boss or extension 14 and said washer and its boss or extension 55 are provided with a vertical opening 15.

16 is a valve stem extending through the

packing ring and provided at its lower end with a circular recess 17 wherein fits a thin metallic washer 18 and a fiber or equivalent disk valve 19, and to secure said disk valve 60 and washer reliably in position a screw bolt 20, extends up through them into stem 16, the said bolt having an inverted conical head 21 of such size that it materially restricts the volume of water which can pass 65 up through passage 7 when the valve is only partly raised or opened, it being noted that as the valve is lifted higher and higher the tapering head of the bolt permits water in greater volume to pass through said passage. 70 By this arrangement therefore, the possibility of the water being turned on suddenly with sufficient force to cause it to splash out of the bowl, is avoided. It will also be noted that by having the abutting faces of 75 the valve stem and washer 18 ground smooth, it is possible for the stem to turn after the disk valve has been pressed against the valve seat 8, and thus avoid undesirable wear on the said disk valve whereby its 80 period of service is extended.

22 is an enlarged externally-threaded portion of the valve stem engaging the threads of the extension 9, and 23 a circular channel or annular recess formed in the upper end 85 of said threaded portion of the valve stem, receiving the depending boss of the packing ring, and fitting on the stem 16 at the upper side of the packing ring, is an auxiliary packing ring 24.

25 is the customary internally-threaded cap, screwed upon the upper end of extension 9, and provided with a central opening 26 through which stem 16 extends, said opening being of increased diameter at its 90 lower end to snugly receive the auxiliary packing ring 24. The cap is formed with an inwardly-disposed shoulder 27 which engages the upper side of the packing ring and clamps the same and washer 12, firmly down 100 into the recess 11.

The upper extremity of the stem 16 is vertically corrugated at 28, and socketed on said stem is a metallic body 29 of a handle 30 of any suitable material. The upper end 105 of the socket 31 of said body is corrugated at 32 to fit snugly and non-rotatably upon the corrugated upper end of the stem, the arrangement being such that the handle can be secured upon the stem to point in the 110 same direction as the spout, without regard to how the stem is secured in the body of

the faucet, that is to say, by means of the corrugated portions of the stem and handle, a fine adjustment of the latter may be effected and to secure the handle reliably upon the stem, a screw bolt 33 extends through the body 29 into the upper end of the stem, as shown.

When the faucet is opened by turning the handle in the proper direction to raise the 10 valve from its seat, the water passes from chamber 2 through passage 7 into chamber 4 and thence through the spout, the volume increasing gradually as hereinbefore explained, because the downwardly-tapering 15 head of the bolt offers a diminishing obstruction to the passage of the water through passage 7. Because of this there is no chance for a large volume of water to be suddenly projected through the spout as 20 the opening of the valve takes place.

The cap 25 by clamping the packing ring 13 tightly in the recess 11 of the extension 9, guards against the passage of water upwardly and around said ring and water is 25 prevented from passing outwardly through the opening of the packing ring because upward movement of the stem results in clamping the boss of the packing ring tightly upon the stem. The passage of wa- 30 ter through the cap is further guarded against by the use of the packing ring 24 wedged in the lower end of the opening 26 of the cap around the stem and upon the packing ring 13.

35 As herein before referred to, the stem has a swivel action on washer 18 to reduce wear on the disk valve and the swivel action may also occur in the initial turning of the handle to open the valve, it being obvious that 40 there is more friction engendered by the engagement of the disk valve with the valve seat 8 and between the disk valve and the washer 18, than there is between the latter

and the bottom of the valve stem. The advantage of giving the handle a fine adjustment on the stem is mainly one of appearance, that is to say it is desirable especially where there are two similar faucets attached to the same fixture, that the handle of each shall project in the same direction as the 50 spout when the faucets are closed.

From the above description it will be apparent that I have produced a compression faucet embodying the features of advantage enumerated as desirable, and while I have illustrated and described the preferred embodiment of the invention I reserve the right to make all changes falling within the spirit and scope of the appended claim.

I claim:

A faucet having an internally and externally threaded tubular extension provided with an interior step portion adjacent its outer edge, a valve stem having an enlarged portion threaded through said extension, said 65 enlarged portion having an annular recess opening in the direction of the axis of the stem, a cap engaging the external threads of said extension and fitting around the stem and forming with said stem an annular 70 recess wedge-shaped in cross section, a packing ring fitting in the first-named annular recess and having a shoulder engaged by said cap and seated in said step portion of the extension, and an auxiliary packing 75 ring abutting against said first ring and adapted, as said cap is screwed in place, to be wedged by said first ring into the recess in said cap.

In testimony whereof I affix my signature, in the presence of two witnesses.

JOHN P. FARLEY.
